UNITED STATES PATENT OFFICE.

JOHN EDWARD THORNTON, OF ROCHESTER, NEW YORK, ASSIGNOR TO JOHN OWDEN O'BRIEN, OF MANCHESTER, ENGLAND.

APPARATUS FOR PERFORATING CINEMATOGRAPHIC FILMS.

1,169,097.

Specification of Letters Patent.

Patented Jan. 18, 1916.

Application filed May 9, 1913. Serial No. 766,596.

To all whom it may concern:

Be it known that I, JOHN EDWARD THORNTON, a British subject, residing at Rochester, New York, United States of America, have 5 invented certain new and useful Improvements in Apparatus for Perforating Cinematographic Films, of which the following is a specification.

This invention relates to the perforating 10 of cinematograph or motion picture films after the film is printed, developed, dried, shrunk and finished and which can take place when the film is capable of being exposed to light, and is applicable for example to films described in my application Serial No. 733633, filed Nov. 26, 1912, though it may be applied to any single width or multi-width film which is to be perforated after being printed.

20 The machines hitherto used for perforating films have been constructed with reciprocating punches, feed apparatus to engage the perforations and draw the film forward and adjusting mechanisms to adjust 25 and determine the distance between the punch holes.

My invention consists essentially in the application to or combination with film punching machines having an adjustable 30 feed mechanism of means for visually inspecting the pictures as perforation of the film progresses in order that the operator may adjust the perforations to any variations in the pictures due to shrinkage or 35 other causes.

The invention will be fully described with reference to the accompanying drawings.

Figure 1. is a sectional elevation of film punching machine with the invention applied thereto. Fig. 2. is a diagram showing the simplest form of the invention. Fig. 3. is a sectional elevation of a modified construction of the machine. Fig. 4. is a transverse sectional elevation of same. Fig. 5. is a plan. Figs. 6 and 7. are transverse sectional elevation and plan showing a modified arrangement. Fig. 8. is a diagrammatic plan showing several machines working together.

50 The film punching apparatus may be of known construction with a table A, punches B, feed apparatus C and mechanism D with an indicating finger d for positioning the film before each perforation is punched as in Figs. 1, 6 and 7. Or the feed apparatus

C may be constructed with a horizontal hooked arm c and an adjustable fulcrum c' as in Figs. 3, 4 and 5, the fulcrum c' being carried by a stud or bolt c² raised and lowered by a nut c³. To the nut an indicating 60 finger or lever d is attached over a calibrated sector plate c⁴, by which the position of the fulcrum c' and with it the feed of the arm c can be altered and adjusted as the punching progresses. 65

In order to insure proper results, the film feeding means C engages perforations which have been previously made in the film by the punches B. The film feeding devices shown are given as examples, and 70 it is to be understood that the present invention is not limited thereto.

To the punching machine I apply means for visually inspecting the pictures as they are moved forward in succession so that the 75 operator may see after each perforation is punched the relative position of the picture to the perforation and whether any adjustment is required. In its simplest form this may comprise an illuminated panel E and 80 an electric or other light F with a gage or index thereon over which the film travels so that the operator may constantly observe the film. This observation may be done by the naked eye as in Figs. 2 and 3 by means 85 of the lamp F placed below an aperture in a panel placed in the table of the machine.

In order to render the inspection more easy and reliable I prefer to illuminate the 90 film with a powerful light F and by means of a lens or lenses G project an enlarged image of the picture onto a screen H.

The light F may be placed above the film with a reflector g and lens G below it and 95 a vertical screen H in front of the machine as in Fig. 1. Or the light F may be placed at one side of the machine with a reflector g, below the film to direct the light through it and a reflector g' and a lens or lenses G 100 above the film to project the picture on to a vertical screen as in Figs. 6, 7 and 8.

The lens or lenses G, the light F, and the reflector g may be arranged in any other optical combination by which the picture 105 from the film will be projected onto a screen either vertical or horizontal. For example the lens light and reflector may be all above the film and the picture projected by reflected instead of transmitted light.

For a multi-width or multi-color film two or more lenses may be employed one for each section of the film and if desired these may be arranged to superimpose the pictures on the screen so that they can be inspected in their complete colors as shown at H' Fig. 8.

It will be found most convenient to place the screen H vertically—such as on the wall of the workroom—and in that case one operator is able to readily inspect, check and superintend the work of several machines at a time, passing a glance over a row of projected images, and instantly adjusting the feed adjustment of any machine requiring adjustment as in Fig. 8. To facilitate the rapidity and accuracy of such tests the panel or aperture, through which the picture is projected, or the screen, is provided with gage dies, masks, or other indicators, to show whether the position of a picture is getting out of truth or not. By this arrangement the slightest variation in the picture from shrinkage of the film or other cause can be readily detected and eliminated so as to secure correct registration. Multi-width films are perforated across all the sections simultaneously at one operation of the punch thereby securing that the latter will accurately register when superimposed.

In producing cinematographic films by present known methods, the film is perforated first, then printed, and registration of each picture in its proper position is insured because every picture is printed singly and the film fed or drawn forward by mechanism which engages with the perforations. As the perforations are accurately spaced all the same distance apart, the film is always drawn forward the same distance, and the pictures are therefore always printed centrally in the space allotted to them. Such is possible because the films used are of the rapid variety (such as gelatino-silver bromid) which require only a fraction of a second for each exposure. But in producing cinematographic films by the new method, the sensitized material is of the slow variety (such as gelatino-bichromate), requiring an exposure of about five to fifteen minutes for every picture. Therefore, while it is technically possible to print by this slow process on film which has been perforated before hand and thereby insure the same accuracy of registration as would be secured when using a more rapid process, it will be obvious that it would have no commercial value because of the excessively long exposure and consequently small output per hour. This question of output is dealt with by printing as many pictures at a time by the slow process as are necessary to bring the output per hour up to the same as by the rapid process. This is effected by exposing a very long length of the film (say 1000 pictures at a time) to an extended streak of light

emitted by a lamp of such character that the heat generated is insufficient to damage the celluloid film during the long exposure necessary. But if the slow sensitized film is perforated before printing, with regular spacing 70 as used for rapid sensitized film, it will be found, when the negative and sensitized films are extended and their perforations compared, that the perforations in the two films do not coincide, the sensitized film particularly being wrong. The effect of this discrepancy is, that when the sensitized film has been printed, developed, washed and dried, and its pictures are projected in magnified form upon the lantern screen, the pictures 80 will climb up or down on the screen, because the perforations by which the film is moved through the lantern do not register with the pictures. This fault can only be overcome by perforating the film after it is printed, 85 and by altering the spacing of the perforations to make them correspond with the picture—just the opposite of the system used in regular practice, where the pictures are made to correspond with the perforations instead. 90 Only by perforating in this way is it possible to produce successful pictures by slow printing processes.

When perforating the rapid sensitive film for the old gelatino-silver process the film is 95 perforated while in its sensitive condition, and in total darkness, and by automatic machinery, no visual inspection of the film during the process being necessary. But when perforating films made by the new 100 process, because perforations have to be adjusted to suit the positions of the finished pictures, it is necessary to inspect the pictures during perforation, and this is most conveniently done by projecting an enlarged 105 image of same onto a suitable screen. By this means a very slight variation in the position of each picture is readily shown, and the error is immediately corrected by the operator moving a pointer or other device 110 that will shorten or lengthen the feed stroke of the film shifting mechanism. It will therefore be understood that cinematographic films by this new process cannot be satisfactorily perforated except in the manner indicated by this invention, viz., after development, and by aid of projection, and by aid of an adjustable perforating machine 115 combined.

What I claim as my invention and desire 120 to protect by Letters Patent is:—

1. In a machine for perforating printed cinematographic films, the combination of film punching devices, gaging means located in predetermined relation to the punching 125 devices for affording visual inspection of the pictures on the printed film during perforation thereof, and mechanism co-operative with perforations previously made in the film by the punching devices for advancing 130

the film to receive perforations for the successive pictures, said mechanism being adjustable to vary the extent to which the film is advanced at each operation.

- 5 2. In a machine for perforating printed cinematographic films, the combination of film perforating devices, gaging means in predetermined relation to the perforating devices for transmitting light to the printed 10 film during the perforating operation and to afford optical inspection thereof, means co-operative with perforations previously made in the film by the perforating devices for advancing the film to receive perforations for 15 the successive pictures, and means for varying the extent to which the film is advanced at each operation by the feeding means.

3. In a machine for perforating printed cinematographic films, the combination of film perforating means, film feeding means 20 co-operative with the perforations previously made by the perforating means, and picture-gaging means in predetermined relation to the perforating means for projecting an enlarged image of the picture on the printed 25 film during the perforating operation.

In testimony whereof I have hereunto set my hand in presence of two subscribing witnesses.

JOHN EDWARD THORNTON.
